(57) **CLAIM**

The ornamental design for an miter gauge, as shown and described.

DESCRIPTION

FIG. 1 is an isometric view of a miter gauge showing a support portion, a slide guide portion, and an arm portion in juxtaposition;

FIG. 2 is an isometric view of the support portion of the miter gauge;

FIG. 3 is a front view of FIG. 2;

FIG. 4 is a rear view of FIG. 2;

FIG. 5 is a left-hand side view of FIG. 2, illustrated as an exploded view for detail, wherein a right-hand side view is a mirror image of the left-hand side view;

FIG. 6 is a top view of FIG. 2;

FIG. 7 is a bottom view of FIG. 2;

FIG. 8 is a close-up isometric view of the slide guide portion of the miter gauge;

FIG. 9 is a front view of FIG. 8;

FIG. 10 is a rear view of FIG. 8;

FIG. 11 is a left-hand side view of FIG. 8, wherein a right-hand side view is a mirror image of the left-hand side view;

FIG. 12 is a top view of FIG. 8;

FIG. 13 is a bottom view of FIG. 8;

FIG. 14 is an isometric view of the arm portion of the miter gauge;

FIG. 15 is a front view of FIG. 14, wherein a rear view is a mirror image of the front view;

FIG. 16 is a left-hand side view of FIG. 14;

FIG. 17 is a right-hand side view of FIG. 14;

FIG. 18 is a top view of FIG. 14;

FIG. 19 is a bottom view of FIG. 14; and,

FIG. 20 is another isometric view of the miter gauge, having each portion compiled together with a fastening mechanism shown as the environment for illustration.
